United States Patent Office.

CHENEY KILBURN, OF PHILADELPHIA, PENNSYLVANIA, ASSIGNOR TO
KILBURN & GATES, OF SAME PLACE.

Design No. 4,351, dated September 13, 1870.

DESIGN FOR THE BOXES FOR THE TOPS OF BUREAUS.

The Schedule referred to in these Letters Patent and making part of the same

I, CHENEY KILBURN, of Philadelphia, county of Philadelphia, State of Pennsylvania, have invented or produced a Design for Boxes for the Tops of Bureaus, of which the following is a specification.

Figure 1 is a perspective view, representing my design for a box for the tops of bureaus, and

Figure 2, a plan view of the same in outline.

This design relates to a box intended to be placed upon the top of a bureau for the support of the looking-glass standards.

The box is of the usual oblong form, and has a hinged lid, *a*, rounded corners *b b*, and two projections, *c c*, in front, these latter forming the main peculiarity of the design.

The box may also, if desired, have projections *x x* at its opposite ends, as indicated by dotted lines in fig. 2.

The molding or finish of the edge of the box is, it will be understood, extended around the projections *c c*, and around the projections *x*, also, if the latter are employed.

I claim—

The design for boxes for the tops of bureaus, substantially as described, and as illustrated in and by the accompanying drawing.

In testimony whereof I have signed my name to this specification in the presence of two subscribing witnesses.

CHENEY KILBURN.
